UNITED STATES PATENT OFFICE.

WILLIAM H. TOWERS, OF NEW YORK, N. Y.

CLOTHES-PIN.

Specification of Letters Patent No. 24,503, dated June 21, 1859.

To all whom it may concern:

Be it known that I, WILLIAM H. TOWERS, of the city, county, and State of New York, have invented a new and useful Improvement 5 in Clothes-Clamps; and I do hereby declare that the following is a full, clear, and exact description of the same, reference being had to the accompanying drawings, making part of this specification.

10 Figure 1, is a perspective view of two of the improved clamps attached to a clothes line. Fig. 2, is a vertical section through the center of one of the clamps. Fig. 3, is a side elevation of ditto, with the prongs 15 distended to the position they are usually brought before being attached to the line.

Similar letters in the figures refer to corresponding parts.

This invention consists in forming the 20 clamp in two parts and jointing them together at one end, in such a manner as to enable their opposite pronged ends to be opened from each other before being applied to the line, and when closed upon the 25 same, to clamp the clothes securely in their place. The two parts A, of the clamp may be made of any suitable material, and are so formed as to somewhat resemble, when brought together and parallel with each 30 other, the ordinary clothes pin, their lower parts next each other being slightly rounded and tapered so as to form a corresponding slit or space between them, while their upper surfaces next each other, are made 35 flat, so as to enable them to be brought flush

together and to turn past each other. The upper ends of the pieces A, are secured firmly together by a pin or rivet B, having suitable washers or heads at either end, and upon this pin or rivet B, both or either of 40 said parts A, may be freely moved so as to bring their tapered prongs nearer to, or farther from each other as occasion may require.

When it is desired to apply this improved 45 clamp to the line, the prongs are slightly turned from each other to the position represented in Fig. 3, so as to enable them to be placed "astraddle" the line and clothes to be secured thereon. When in this position the simple act of moving the said 50 prongs on their joint pin or rivet B, toward each other, causes them to firmly bind and embrace the clothes and line between them with the required degree of force to prevent 55 their displacement except by the act of opening and unclamping the prongs.

The lower or prong portion of the parts A, may be made so as to have a slight degree of elasticity, if desired. 60

What I claim as new and desire to secure by Letters Patent is—

The before described improved article of manufacture, to wit, a clothes clamp formed of two parts A, jointed together at their upper ends, substantially as set forth. 65
